US00D810774S

(12) **United States Design Patent** (10) **Patent No.:** **US D810,774 S**
Volovik (45) **Date of Patent:** **** Feb. 20, 2018**

(54) **DISPLAY SCREEN OR PORTION THEREOF
WITH GRAPHICAL USER INTERFACE**

(71) Applicant: **GT Gettaxi Limited**, Limassol H.E. (CY)

(72) Inventor: **Anatoly Volovik**, Tel Aviv (IL)

(73) Assignee: **GT Gettaxi Limited**, Limassol (CY)

(**) Term: **15 Years**

(21) Appl. No.: **29/590,014**

(22) Filed: **Jan. 6, 2017**

Related U.S. Application Data

(62) Division of application No. 29/523,696, filed on Apr. 13, 2015, now Pat. No. Des. 780,206.

(57) **CLAIM**

The ornamental design for a display screen or portion thereof with graphical user interface, as shown and described.

DESCRIPTION

The sole FIGURE is a front view of a display screen or portion thereof with graphical user interface showing my new design.

The broken line showing of a display screen and graphical user interface elements are included for the purpose of illustrating portions of the article and form no part of the claimed design.

1 Claim, 1 Drawing Sheet
